(57) **CLAIM**

The ornamental design for a laser measuring instrument, as shown and described.

DESCRIPTION

FIG. 1 is a perspective view of the laser measuring instrument according to our novel design;

FIG. 2 is a front view of the laser measuring instrument of FIG. 1;

FIG. 3 is a rear view of the laser measuring instrument of FIG. 1;

FIG. 4 is a left side view of the laser measuring instrument of FIG. 1;

FIG. 5 is a right side view of the laser measuring instrument of FIG. 1;

FIG. 6 is a top plan view of the laser measuring instrument of FIG. 1; and,

FIG. 7 is a bottom view of the laser measuring instrument of FIG. 1.

The broken line showing is for illustrative purposes only and forms no part of the claimed design.
